DECORATIVE ESCUTCHEON PLATE FOR A LOCK

George T. Patriquin, Gardner, Mass., assignor to Lockwood Hardware Mfg. Co., Fitchburg, Mass., a corporation of Massachusetts

Application July 16, 1954, Serial No. 31,469

Term of patent 14 years

(Cl. D50—6)

I claim:

The ornamental design for a decorative escutcheon plate for a lock, substantially as shown.
